UNITED STATES PATENT OFFICE.

JOHN A. THOMPSON AND AENEAS WELLS, OF PITTSBURG, PA.

BED-BOTTOM FRAME.

SPECIFICATION forming part of Letters Patent No. 258,613, dated May 30, 1882.

Application filed April 10, 1882. (No model.)

To all whom it may concern:

Be it known that we, JOHN A. THOMPSON and AENEAS WELLS, of Pittsburgh, in the county of Allegheny and State of Pennsylvania, have invented a new and useful Improvement in Bed-Bottom Frames; and we do hereby declare the following to be a full, clear, and exact description thereof, reference being had to the accompanying drawings, forming a part of this specification, and in which—

Figure 1 is a longitudinal section of our improvement in bed-bottoms. Fig. 2 is an inner side view of one of the corner-pieces. Fig. 3 is a sectional view, showing the manner of attaching the corner-pieces to the side rails. Fig. 4 is a view showing the corner-piece and a tubular metallic end rail.

Like letters of reference indicate like parts in each.

20 Our invention relates to an improvement in the frames for woven-wire mattresses which form the subject of Letters Patent No. 239,129, granted to us March 22, 1881; and it consists in an improved device for adjusting and fastening the side rails and corner-pieces in a fixed relative position, as described and claimed.

We will now describe our invention, so that others skilled in the art may manufacture and use the same.

30 In the drawings, *a* represents the side rails of the frame, which are made of iron or other metal, preferably, however, of gas-pipe or other tubing, which secures strength and lightness. These side rails are secured to metal corner-pieces *b*, each of which is provided with two sockets, *c* and *d*, one for the side rail and the other for the end rail of the frame, the two sockets being at right angles to each other, and the socket *d* being preferably on a plane 40 above the socket *c* for the side rail, so as to keep the wire mattress stretched above the side rails. The end rails, *e*, may be formed of metal or of wood, as is preferred, both of which forms are shown in the drawings. Both 45 ends of the side rails, *a*, are provided with a screw-thread, and the sockets *c* of the corner-pieces *b* are also threaded, so that by turning the side rails, *a*, the end rails, *e*, will be moved farther apart or drawn nearer to each other, 50 so as to stretch or slacken the wire fabric.

To prevent the side rails from turning in the sockets *c* when the frame receives a jar or is lifted by one of the corner-pieces so as to throw the entire weight upon the corner-pieces,

a set-screw, *f*, passes through a threaded hole, 55 *f'*, in the side of the socket, so as to bite against the threaded portion of the side rails, *a*, as shown in Fig. 3.

The side rails, *a*, are provided with a hole, *h*, into which a rod or tool may be inserted to 60 turn the rails, and thereby lengthen or shorten the frame; but the rails, however, can be easily turned without this by the use of any suitable pipe-wrench.

The end rails, *e*, may be formed of wood and 65 secured in the rectangular sockets *d* of the corner-pieces *b*, or they may be formed of gas-pipe, as shown in Fig. 4, which fits in the sockets *d*, made of corresponding shape. The wire mattress is attached to the two end rails. 70

In case the mattress should become stretched and sag, it may be straightened and hauled taut by turning the side rails, *a*, in the sockets *c* so as to move the end rails, *e*, farther apart from each other, the set-screw *f* being first 75 loosened and then screwed in again after the mattress has been straightened.

The advantages of our invention are that the side rails are securely held from turning in the sockets of the corner-pieces, the frame 80 may be easily and evenly adjusted and secured firmly in its adjusted position, no especial fitting is necessary to make the frame lie level, and it is secured against warping or racking.

Having thus described our invention, what 85 we claim, and desire to secure by Letters Patent, is—

1. A woven-wire-mattress frame consisting of screw-threaded metallic side rails, threaded metallic corner-pieces, having sockets for the 90 end and side rails, in combination with set-screws which pass through the corner-pieces and bear against the threaded portion of the side rails, substantially as and for the purposes specified. 95

2. A mattress-frame having adjustable side rails, provided with a set screw or screws extending through the sockets and biting on the rail fitting therein, substantially as and for the purposes described. 100

In testimony whereof we have hereunto set our hands this 4th day of April, A. D. 1882.

JOHN A. THOMPSON.
AENEAS WELLS.
